CAPSULE FILLING DEVICE

Sam Karos, Detroit, Mich.

Application September 12, 1952, Serial No. 309,179

2 Claims. (Cl. 326—41)

1

The present invention covers capsule filling devices and relates specifically to improved devices for filling or loading capsules of the split hard shelled type with medicinal preparations such as drugs or sedatives.

It is an object of this invention to provide for use by druggists and pharmacists a capsule filling device wherein a plurality of capsules of various cubical capacities may be simultaneously filled, easily and readily capped and simultaneously ejected from the device.

Another object of this invention is to provide an improved device of the aforesaid character including a vertically movable capsule filling-control plate divided into a plurality of sections segregated from each other so as to enable the operator to load or fill the capsule cups of selected sections with the same or different drugs or medicaments, with the cups of each section being graded as to capacity from those of the other sections.

Still another object of this invention is to provide an improved device of the aforesaid character having a vertically movable plate that is adapted to slidably receive and retain thereon selected capsule filling control plates, the operator's choice of which is primarily dependent upon the size or sizes of capsules to be filled and wherein if groups of capsules of different sizes are desired to be simultaneously filled, a plate having sections of segregated capsule retaining and filling orifices of different sizes also to accommodate the capsules, may be selected.

Still another and further object of this invention is to provide an improved device of this character with novel conveniently operable means for releasably locking or holding the vertically movable plates aforesaid in different positions for filling, capping and ejecting the capsules.

The above, other and further objects of the present invention will be apparent from the following description, accompanying drawings and appended claims.

The accompanying drawings illustrate the embodiments of my improved capsule filling device constructed in accordance with the principles of the present invention and the views thereof are as follows:

Figure 1 is a top plan view of an embodiment of the invention showing the movable plate thereof which is provided with a plurality of segregated sections with each section being provided with a plurality of apertures that differ in diametrical dimensions from the apertures of the other sections.

2

Figure 2 is a side view, partly in section, of the device.

Figure 3 is a vertical sectional view of the device along the line 3—3 of Fig. 1.

Figure 4 is a vertical sectional view of the device along the line 4—4 of Fig. 1.

Figure 5 is a vertical sectional view of the device, similar to Fig. 4, but showing the device in capsule ejecting position.

Figure 6 is a top plan view of a modified form of the movable plate shown in Fig. 1, and

Figure 7 is a vertical sectional view taken on the line 7—7 of Fig. 6.

In the embodiment of the invention illustrated in the drawings, Figs. 1 to 5 inclusive, the device there illustrated is composed of two plate members each of which may be made of rigid plastic material. These plates are vertically disposed one above the other in spaced relationship to each other. The bottom, or capsule ejector plate 10 is stationary while the upper or capsule filling control plate member 11 is guided for selective up and down movement relative to the stationary plate by means of the corner posts 14, of which there are four in number. Springs 15 yieldably urge plate 11 upwardly against the heads 16 of each of said posts. The upper surface of plate 11 is divided into a plurality of sections by means of upstanding or vertically disposed walls or partitions 17. It will be seen, Fig. 1, that these walls are so interconnected one with the other as to form a continuous or integral wall composed of several branches which extend in various directions to form barriers or lateral enclosures for each section. Within the confines of said sections the floor of plate 11 is provided with a suitable number of apertures 18 therethrough.

The diametrical dimensions of the apertures in each section are uniform one with the other but that they may differ from those of each of the other sections, as shown in Figs. 1 through 5 of the drawings. However the apertures in the group of sections A, B, C, which sections differ from each other as to number of apertures, are of the same size but they differ in size from the apertures in the group of sections D, E and F, the apertures in these two groups of sections differ in size from the apertures in the group of sections G, H, and I. In each group the different sections exhibit a different number of apertures. It is obvious that each section might differ from every other section as to diameter of apertures if such was desired. The apertures of each group or section are, of course, adapted to receive and hold only those cup portions of capsules which

are adapted to fit into that group's apertures. These cup portions, designated 19, Fig. 3, are inserted in said apertures so that the openings thereto are flush with the floor of the capsule filling control plate 11. Consequently the operator when filling capsules in a certain section or sections with selected medicated powders or granules may scrape along the floor of each section so as to evenly and adequately distribute the filler into the several cups of each section and the walls 17 enable him to confine his activities in the foregoing respects to the specific area within the boundaries of each section's walls. It will, therefore, be understood that with my sectionalized filler cup plate that the operator can utilize one or more sections for filling all its cups with a particular filler while at the same time using one or more of the other sections for other ingredients without danger of mixing such ingredients.

Upon the filling of the cups aforesaid, the next step in the sequence of operations of my machine is to secure a closure cap 20 to each of the aforesaid filled cups. The final step is to simultaneously eject all of the capsules from the plate. To expedite and efficiently effect these operations, I provide a bifurcated operational control lever 21, each arm 22 of which is pivoted intermediate its ends, by means of a pin 23 to a bracket 24, one each of which is carried on opposite sides of the plate 11. Each of said arms, starting at a point approximately in the vicinity of the pivot pins 23 and extending to the outer or free end of each arm, is disposed in angular relationship with the inner portion of each arm and extends in a diagonal direction toward and adjacent to the opposite sides of ejector plate 10. A slot 25 is provided adjacent the extreme end of each arm 22. Pins 26, secured in the opposed sides of plate 10, engage each of said slots to unitedly act as a fulcrum for the lever 21. Thus it will be seen that when the lever 21, which is provided with the handle or knob 27, is pushed downwardly, as shown in Fig. 4, the pivoted connection 23 to said lever and plate 11 will cause the latter to be lowered toward the capsule cup ejector pins 28 disposed in the plate 10, whereupon the lower ends of the cups 19, contacting the upper surfaces of pins 28 will force said cups upwardly in the plate 11 a distance sufficient to enable the closure caps 19 to be secured to said cups.

Upon completion of the capping operation aforesaid, further downward movement of the lever 21 will cause the pins 28 to force the filled capsules to expelled position relative to the filler plate 11.

In the actuation of the control lever 21, it is necessary only to latch or hold the plate 11 during the capping operation aforesaid. This is so because when plate 11 is in its full upward or capsule filling position (Fig. 2) the springs 15 definitely maintain it in that position, and when the plate is manually urged by the lever 21 to its lowermost or capsule ejecting position (Fig. 5) it is necessary only to momentarily hold it in that position until the capsules have been cleared from the plate. Therefore, to effectively hold the plate in the central or capping position a spring, which may be in the form of a flexible metallic member 29, is secured at one end to the rearward portion of the stationary plate 10 and extends arcuately upward so that its intermediate portion abuts and presses against the inner face of the transverse portion of lever 21 adjacent the knob 27. An elongated slot 30 is provided in member

29 into which the inwardly extending pin portion 31 of knob 27 projects for releasable latching engagement therewith of the lever 21 during said capping operation.

5 In the modification of the invention illustrated in Figs. 6 and 7, I have shown a capsule filling control plate only and it is to be understood that this plate is adapted to be used with an ejector or base plate that is identical in every respect with the base plate 10 shown in the heretofore described embodiment of the invention. Like its predecessor this modified capsule filling control plate 32 is positioned vertically above a base plate that is identical with the base plate 10. Plate 32, like plate 10, is guided by posts 33 and is held in yielding engagement against the heads 34 of said posts by springs 35. Plate 32, however, is provided with a plurality of apertures 36 therethrough, the diametrical dimensions of which are uniformly of maximum width to receive therethrough capsules of the greatest capacity. For purposes of clarity in the further description of this modification this plate 32 shall be referred to as the main plate or seat portion of the plate as it is only a part of a composite plate subsequently to be described.

10 The ends and one side portion of said plate 32 are provided with an upstanding flange or rim 37 which is undercut in its inner face to provide a 30 pair of opposed slideways or tracks 38 and 39 that extend transversely from the front face thereof and terminate at the inner junctures of the side portion of the rim with the end portions thereof. Each of the aforesaid tracks is adapted 35 to receive, for slidable engagement therein a flange 40 that is formed to project laterally from the side of a supplemental capsule filling control plate or slide 41.

15 This supplemental plate may have a plurality 40 of apertures 42 therethrough of uniform diameters but of less width than those of the seat plate 32; or, the supplemental slide plate 41 may be 45 sectionalized in a manner similar to that heretofore described with respect to the sections confined by the walls 17, and wherein the apertures of the different groups of each section not only vary in size from those of the adjacent sectional groups but again are of width less than those of the main plate. In Figs. 6 and 7 similar walls 43 are illustrated on the supplemental plate 41 for confining the apertures 42 therebetween.

20 Any one of a number of supplemental plates 39 may be employed with plate 32 in order that 40 capsules of any required capacities may be filled. Thus a plate 41 having two or three sections the 45 apertures 42 of each of which will accommodate 50 capsule cups corresponding to the sizes of such apertures, another plate may have two, three or more sections the apertures of each of which are 55 adapted to receive cups of still different capacities, and so on. Consequently a complete set of 60 supplemental plates for carrying out quantity 65 production of capsule filling operations are provided to speedily and efficiently fill any and all sizes of capsules, which are commercially available.

25 It will be understood that in the use of my supplemental plates 41 and their slidable insertion into the main plate 32, so as to form therewith a composite plate, each aperture in the supplemental plate 41 will axially overlie an aperture disposed in the main plate 32. Thus whatever 30 the diametrical dimensions are of the apertures in the supplemental plate they will always be in 35 positive axial alignment with the related aper-

tures of the main plate, provided that the former plate is pushed all the way back into the slide-ways of the latter, for the number of apertures in each plate is the same and each aperture in each plate is concentrically disposed about a center that passes axially through the apertures of each plate when placed one atop the other. Consequently a cup 19 which is inserted in an aperture 42 will extend therethrough into the larger aperture 36 of the main or seat plate 32 so that the pins 28 may contact same, upon manipulation of lever 21 as aforesaid, and force the capsules first upwardly for filling and then expel them out of the composite plate.

What I claim is:

1. A capsule filling machine comprising, in combination, a stationary plate having a plurality of upstanding ejector pins, a sectionalized capsule filling control plate supported above the first mentioned plate for relative vertical movement toward and away from said plate, spring means normally yieldingly urging the control plate away from the stationary plate, upstanding walls provided on the upper face of the control plate defining the sections thereof, each section being provided with a plurality of spaced cup-receiving and supporting perforations differing in diameter from those of each other section, a lever pivotally connected to each of said plates for moving the control plate toward the ejector plate, and a spring latch operable on movement of said lever to releasably retain it and hold the control plate from movement relative to the ejector plate.

control plate from movement relative to the ejector plate.

2. A capsule filling machine comprising, in combination, a stationary plate having a plurality of upstanding ejector pins, a sectionalized capsule filling control plate supported above the first mentioned plate for relative vertical movement toward and away from said plate, spring means normally yieldingly urging the control plate away from the stationary plate, upwardly projecting walls provided on the upper face of the control plate defining the sections thereof, each section being provided with a plurality of spaced cup-receiving and supporting perforations differing in diameter from those of each other section, a lever pivotally connected to each of said plates for moving the control plate toward the ejector plate, and a spring latch mounted on one of said plates and operable on movement of said lever to releasably retain it and hold the control plate from movement relative to the ejector plate.
